(57) **CLAIM**

The ornamental design for a shaver handle, as shown and described.

DESCRIPTION

FIG. 1 is a top, back perspective view of our new design for a shaver handle, the shaver head being shown in broken lines and thus not forming a part of the claimed design;

FIG. 2 is a back elevational view thereof;

FIG. 3 is a left side elevational view thereof;

FIG. 4 is a top plan view thereof;

FIG. 5 is a bottom plan view thereof; and,

FIG. 6 is a front elevational view thereof.

The broken lines immediately adjacent the shaded areas represent the bounds of the claims. All other broken lines are for illustrative purposes only. None of the broken lines form a part of the claimed design.
